UNITED STATES PATENT OFFICE.

WILLIAM A. PATTEN, OF LESUEUR, MINNESOTA.

MATCH-BOX.

SPECIFICATION forming part of Letters Patent No. 671,656, dated April 9, 1901.

Application filed November 12, 1900. Serial No. 36,173. (No model.)

To all whom it may concern:

Be it known that I, WILLIAM A. PATTEN, a citizen of the United States, residing at Lesueur, in the county of Lesueur and State of Minnesota, have invented certain new and useful Improvements in Match-Boxes; and I do hereby declare the following to be a full, clear, and exact description of the invention, such as will enable others skilled in the art to 10 which it appertains to make and use the same.

My invention relates to match-boxes, and has for its object to provide certain improvements therein, whereby the same box is adapted for use both as a shipping-box and as a 15 holder, with an individual delivery for the matches.

To this end my invention consists of the novel devices or features of construction hereinafter described, and defined in the claims.

20 My improved box is illustrated in the accompanying drawings, wherein like notations refer to like parts throughout the several views.

In said drawings, Figure 1 is a plan view of 25 the box with a portion of the cover broken away, showing the parts as they would appear when using the box in the ordinary way for shipping purposes. Fig. 2 is a similar view of the same parts in side elevation and 30 partial vertical section. Fig. 3 is an end elevation looking at what becomes the lower end of the box when the same is suspended for use as a holder. Fig. 4 is a similar view of the opposite or upper end of the box. Fig. 5 is a view in front elevation, showing the box 35 as it would appear when suspended on the wall for use as a holder. Fig. 6 shows the box in the same position in vertical longitudinal section, and Fig. 7 is a plan view illustrating the blank from which the tray shown in 40 the other views can conveniently be formed.

The cover or shell *a* is open at both ends and is of the same identical form as that commonly used for matches. The tray *b* differs 45 from the ordinary form, although capable of the ordinary use. To adapt the tray for co-operation with the cover *a* to afford a holder with individual match-delivery, I modify the construction as will now be noted.

50 One of the end walls of the tray is provided with one or more match-retaining fingers or flaps *b'*, which are adapted either to under-

lie or overreach the face of the cover *a*. Preferably the lower end wall of the tray is formed of two spring sections or fingers *b'*, laterally spaced apart from each other and not connected to the side walls of the tray. Said fingers *b'* are of a greater length than the depth of the tray, thus adapting them to overreach the top of the body of matches and 60 underlie the cover of the box when the parts are in the position shown in Figs. 1 and 4 and to overreach the face of the box-cover when the parts are in the position shown in Figs. 5 and 6. The side walls of the tray *b*, 65 adjacent to the spring-fingers *b'*, are extended to afford guard-flaps *b*², which co-operate with the fingers *b'*, when the parts are in the position shown in Figs. 5 and 6, to prevent end-wise displacement of the matches. The 70 spring-fingers *b'* are laterally spaced apart from each other to afford access to the matches when the box is in use as a suspended holder. At its opposite or upper end the tray *b* is provided with some suitable suspending device, 75 which may conveniently be a flap *b*³, cut out on three sides from the upper end wall of the tray, as shown. This flap *b*³ is shown as provided with suitable suspending-holes *b*⁴ for suspending the box when using the same as 80 a holder from a nail *b*⁵ or other overhead support. It is preferable to employ two suspending-holes and suspend the holder from two nails, so as to keep the holder from pivotal motion when withdrawing the matches. 85

All the parts of the box are preferably made from paper-board, just as the ordinary box. Slight additional stock is required for the spring fingers or flaps *b'*. No additional stock whatever is required for use at the opposite 90 end of the tray. The suspending-flap *b*³ is simply stamped out from the ordinary end wall-piece of the blank. The parts which are to form the spring-fingers or retaining-sections *b'* should be so sized as to insure sufficient spring action to permit the same to occupy the relative positions required when the box is in use either for the shipping purposes or as a holder. 95

When the box is suspended for use as a 100 holder, as illustrated in Figs. 5 and 6, it is obvious that the matches will be upheld by the retaining spring-fingers *b'*, but that they may be readily removed one or a few at a time by

raising the same upward along the inner surfaces of the spring-fingers b' . The guards b^2 extending from the side walls of the tray prevent the matches from falling out or being moved out endwise without violence to the guards. In handling the box to convert the same from the shipping use to its use as a holder the tray is simply shoved out of the cover until the fingers b' are free from the cover, and is then again pushed or pulled inward to bring the fingers over the face of the cover. The box is then suspended by springing out and applying the suspending-flap b^3 at the upper end of the tray, and the holder is ready for use.

From the foregoing it is obvious that by extremely slight changes, adding little, if anything, to the expense, the shipping-box becomes itself capable of use as a holder with an individual delivery of the matches.

What I claim, and desire to secure by Letters Patent of the United States, is as follows:

1. In a match-box, the combination with an open-ended cover, of a tray having a match-retaining finger or flap at one end, adapted either to underlie or overreach the face of the cover, whereby the same box is adapted for use either as a shipping-box or as a holder, substantially as described.

2. In a match-box, the combination with an open-ended cover, of a tray having a match-retaining finger or flap at one end, adapted either to underlie or overreach the face of the

cover, and provided, at its opposite end, with means for suspending the box, whereby the same box is adapted for use either as a shipping-box or as a suspended holder having a bottom match-delivery, substantially as described.

3. In a match-box, the combination with an open-ended cover, of a tray having one of its end walls made up of laterally-spaced spring sections or fingers of greater length than the depth of the tray, adapted either to underlie or overreach the face of the cover, and having, at its opposite end, means for suspending the box, substantially as and for the purposes set forth.

4. In a match-box, the combination with an open-ended cover, of a tray having one of its end walls separated from its sides and made up of laterally-spaced spring sections or fingers of greater length than the depth of the tray adapted either to underlie or overreach the face of the cover, and having its adjacent side walls extended outward to afford guard pieces or flaps, for coöperation with said spring-fingers, when the box is in position to act as a holder with individual match-delivery, substantially as described.

In testimony whereof I affix my signature in presence of two witnesses.

WILLIAM A. PATTEN.
